DISPENSING HOSE

Earl E. Eickmeyer and H. Hix Wolfe, Dayton,
Ohio, assignors to The Dayton Pump and Mfg.
Company, Dayton, Ohio, a corporation of Ohio

Application October 31, 1947, Serial No. 783,330

2 Claims. (Cl. 138—49)

1

The present invention deals with a dispensing hose that is commonly associated with a gasoline pump for the purpose of conveying gasoline from the pump to the gasoline tank to be filled, such as that of an automobile.

At the present time, operators of service stations and other places engaged in the commercial dispensing of gasoline, often experience inconvenience in positioning the automobile, having the tank to be filled, with respect to the pump. This difficulty may be attributed largely to the fact that the hoses now associated with the pumps are not sufficiently long to afford a wide latitude in the position of the car with respect to the pump.

The obvious answer to this unsatisfactory condition is to make the hose longer. However, should the now available hose be so lengthened, they become unwieldy and their storage when not in use presents a serious problem. Under present day conditions, the length of a hose is limited to one turn or fold which may be hung on the pump. That is, it is not now practical to have a hose any longer than one which may extend downwardly from its point of connection to a point adjacent to the ground and then upwardly to a rack for the nozzle.

With the foregoing conditions in mind, the present invention has in view, as its foremost objective, the provision of a hose intended for gasoline dispensing purposes which is so designed and constructed so as to include self-coiling properties. When such a hose is used, it normally returns to a coiled position without entailing any coiling operation on the part of the operator. It may be pulled from its coiled position against the influence of a spring means which retains it therein, and therefore does not require any more attention from the operator than the now known hose.

In attaining the above noted objective, a yieldable element is associated with a certain section of the hose length in such a manner as to cause that section to assume a coiled position when all external forces are removed. The presence of this coiled section which may embrace a plurality of coils or turns permits the use of any desired length of hose with any conventional present day gasoline pump under the same conditions of attachment and bracketing at the nozzle end.

A further objective of the invention lies in the provision of a gasoline dispensing hose of the type above indicated, together with a spring that is coiled about a predetermined intermediate section thereof. This spring causes that section

2

to assume a coiled condition when any exterior distorting forces are removed.

Another object of the invention is the provision of a gasoline dispensing hose of the character aforesaid, in which the usual composite rubber wall structure of the hose is supplemented by a strip of rubber composition or comparable material over a predetermined length and in which strip is embedded a leaf spring which normally maintains that portion of the hose in a coiled condition.

Yet another object of the invention is the provision of a modification in which the hose proper is provided with a casing extending partially rearward and over a predetermined intermediate length. This casing is preferably of a rubber composition comparable to that from which the hose is made and each free edge of the casing has embedded therein, a spring strip. These spring strips normally retain that portion of the hose over which they extend in a coiled condition.

Various other and more detailed objects and advantages of the invention such as arise in connection with carrying out the above noted ideas in a practical embodiment will in part become apparent and in part be hereinafter stated as the description of the invention proceeds.

The invention therefore comprises a gasoline dispensing hose having an intermediate length provided with spring means for normally retaining said length in a coiled condition.

For a full and more complete understanding of the invention, reference may be had to the following description and accompanying drawings wherein:

Figure 1 is a perspective view of a gasoline pump and a portion of an automobile having its gas tank connected to the pump by a dispensing hose designed in accordance with the precepts of this invention;

Figure 2 is a view in end elevation of the pump with the hose coiled and stored in its non-used position. This view develops certain broken line positions of the hose illustrating the manner in which it may be extended;

Figure 3 is a view in side elevation of the pump and hose shown in Figure 2;

Figure 4 is a transverse section taken on an enlarged scale through the hose shown in Figures 1, 2, and 3;

Figure 5 is an enlarged detailed perspective of one modification and shows the coiled portion of the hose in detail;

Figure 6 is a similar view of another modification;

Figure 7 is a transverse section through the hose of Figure 5 being taken on an enlarged scale and about on the plane represented by the line 7—7 of Figure 5; and

Figure 8 is another sectional view through the form of hose shown in Figure 6. This view is taken on an enlarged scale and about on the plane represented by the line 8—8 of Figure 6. 10

Referring now to the drawings wherein like reference characters denote corresponding parts and first more particularly to Figure 1, an automobile is represented at A. This automobile includes a gas tank designated 10 and which tank includes the usual spout 11 which is employed for the purpose of filling the tank with gasoline. A gasoline pump is represented at P and a hose referred to generally as H conveys gasoline from the pump P to the spout 11.

It is evident that if the hose H is short, as are the present day hoses of this type, the car A must be parked close to the pump P; otherwise, the hose will not reach and the gasoline cannot be dispensed to the car. However, with the longer hose H, as provided by this invention, a much greater latitude is afforded in the position which the car A may assume with respect to the pump P.

Referring now more in detail to Figures 2 and 3, the pump P is shown as including an outlet fitting at 12. The hose H at one end carries a coupling 13 which is connected to the fitting 12. The other end of the hose H carries a discharge nozzle 14 which, when the hose is not used, is positioned in a supporting bracket 15 carried by the pump P.

The hose H includes a section intermediate its ends which is encased by a coil spring 16. This spring 16 is shown in detail in Figure 4 and may be made from any appropriate spring wire which has the ability of causing the intermediate section of the hose to assume the coiled position depicted in Figures 2 and 3. This coiled condition presents the coils designated C₁, C₂, and C₃.

It is evident that with the presence of the coils C₁, C₂, and C₃ it is possible and entirely practical to support a long length of hose from the fitting 12 and bracket 15 in the manner which is now customary in this field. When an operator is desirous of using the hose, he merely removes the nozzle 14 from the bracket 15 and pulls the hose out sufficiently far to reach the spout 11 of the automobile A. If the automobile should be removed, the maximum distance from the pump, the hose H will be stretched out sufficiently straight such as represented by the broken line portion of Figure 2, which is designated 17. If the automobile A should be just a little closer, the hose H will have a slight coil or bend therein, as represented by the broken lines at 18 of Figure 2.

It is still possible to accommodate close positioning of the car with respect to the pump as the broken line condition of the hose represented at 19 in Figure 2 shows a full coil in the hose. Thus, the car may be positioned under a wide range with respect to the pump P.

First modification

Referring now more particularly to Figures 5 and 7, a modified form of the invention will

be described. In this form, all of the other structure above described remains substantially the same with the exception that the coil spring 16 is replaced by a leaf spring 20 that is embedded 5 in a strip 21 of a rubber composition that is comparable to the wall structure 22 of the hose. The normal tendency of the spring 20 is to cause the hose H to assume the coiled condition illustrated.

However, the hose may be pulled from this coiled position when the operator exerts sufficient force to overcome this tendency of the spring 20. When the distorted force is removed, the hose retains in its coiled position.

Second modification

Figures 6 and 8 develop still another modification. In this form a casing 23 of a rubber composition or comparable material partially encases the circular wall structure 22. The casing 23 has free edges 24 and 25 in each of which is embedded the spring strips 26 and 27, respectively. The casing 23 extends over the intermediate section of hose H which is to be coiled 25 when the hose is not used, and the spring strips 26 and 27 perform this function in the manner above described.

While preferred specific embodiments of the invention are hereinbefore set forth, it is to be clearly understood that the invention is not to be limited to the exact constructions illustrated and described because various modifications of these details may be provided in putting the invention into practice within the purview of the appended claims.

What is claimed is:

1. In a gasoline dispensing hose, a length of hose having a wall structure defining a conduit therethrough, a first opening at one end of said hose, a second opening at the other end of said hose, said wall structure having an intermediate section, a strip anchored to said section on the outer side of said wall structure and extending longitudinally therethrough, and a leaf spring embedded in and extending longitudinally along said strip, said leaf spring normally maintaining said section in a coiled condition.

2. In a gasoline dispensing hose, a length of hose having a wall structure defining a conduit therethrough, a first opening at one end of said hose, a second opening at the other end of said hose, said wall structure having an intermediate section, a casing partially enclosing said section and presenting free edges, and a spring strip embedded in each of said edges, said spring strips normally maintaining said section in a coiled condition.

EARL E. EICKMEYER.
